TORQUE INDICATING AND TRANSMITTING TOOL

Oren B. Harmes, Algona, Iowa

Application July 18, 1956, Serial No. 42,287

Term of patent 14 years

(Cl. D54—16)

Fig. 1 is a perspective view of my torque indicating and transmitting tool embodying my new design;

Fig. 2 is a top plan view of the same;

Fig. 3 is a bottom plan view of the same;

Fig. 4 is a front elevational view of the same;

Fig. 5 is a rear elevational view of the same;

Fig. 6 is a side elevational view of the same as viewed from the left in Fig. 4; and

Fig. 7 is a side elevational view of the same as viewed from the right in Fig. 4.

I claim:

The ornamental design for a torque indicating and transmitting tool, as shown.
